H. J. Wescott INVENTOR

UNITED STATES PATENT OFFICE.

HARRIET J. WESCOTT, OF SOMERVILLE, MASSACHUSETTS.

PROTECTOR FOR LADIES' BOOTS.

SPECIFICATION forming part of Letters Patent No. 519,053, dated May 1, 1894.

Application filed June 17, 1891. Serial No. 396,618. (No model.)

To all whom it may concern:

Be it known that I, HARRIET J. WESCOTT, of Somerville, in the county of Middlesex and State of Massachusetts, have invented an Improved Guard or Protector for the Finished Surfaces of Ladies' Boots, of which the following is a full and exact description when taken together with the accompanying drawings and the reference letters thereon.

10 The nature of my invention relates to a very simple device having the two members *a* and *b*, and not to a device for enveloping the boot, shoe, or ankle, as a general protecting, warmth giving or moisture excluding contrivance, but 15 is limited exclusively to a device having two distinct members, which may be made of separate pieces of material and connected together, or may be cut from a single piece, together with its connecting strips or bands.

20 I am well aware that variously devised over gaiters and protectors for the foot, ankle, and boot or shoe, have been made heretofore. Therefore the nature of my invention relates exclusively to a device having the two members 25 above referred to, viz: one having a delicate tongue-like extension downwardly toward the toe, on and over the central, longitudinal ridge of the instep or upper ridge of the foot, and a corresponding tongue-like extension 30 also in the opposite direction, upwardly in front of and on the central ridge of the instep and ankle forward. This comprises one member. The other member is of a somewhat similar character, viz: a member having a downwardly extending tongue-like projecting part or extension toward the base of 35 the heel, and another upwardly extending tongue-like extension upon and behind the ankle and heel. These parts are formed or 40 cut into as delicate and tasteful a pattern and proportions as is consistent with the practicability of keeping them when properly stiffened, in their normal shape and position. These 45 two members are then connected by suitable strips, straps, or bands as indicated in the drawings. The straps or bands should be made as delicate and inconspicuous as is possibly consistent with the required strength, and to avoid covering any more of the 50 surface of the boot or shoe than is absolutely required for the purpose of securing the two prominent members above described.

The use and purpose of the two members referred to, and of the invention as a whole, is not to give warmth or protection to the foot 55 or ankle, and not in general to protect the boot or shoe, or the boot or shoe uppers, as a whole. On the contrary, it is a leading object to avoid added warmth, and as the drawings illustrate, and the description sets forth, 60 the device is exclusively intended, designed and constructed for protecting the central front and the central rear portion of the surface alone; the finished and ornamental surface only of foot wear, or boots and shoes. 65 No gaiter or protector known to the inventor, and they are many, proposes to accomplish this purpose; no one is constructed with any adaptation to this purpose, and certainly none have accomplished it, nor do they even approach such a result. In other words, all are 70 utterly useless for the specific purpose set forth in this application.

In the drawings the words instep and heel are inscribed on these parts respectively, to 75 indicate the part of the boot that each member is to protect.

The nature of my invention may further be said to relate to the protection of the finished surface of the boot and not at all to give 80 warmth or protection to the wearer's foot. It is consequently made of a very light and delicately formed shape, covering as far as possible only those parts of the boot most exposed to the chafing action of skirts, &c., the 85 ridge of the boot or shoe from the toe centrally up the instep and ankle, and the central rear of the boot, up and down.

The invention as already intimated consists of two prime members viz: *a* *b* instep and 90 heel. These may be shaped in any pleasing and artistic form so that they properly fit and guard the two principally exposed parts of the finished surface of the boot viz: the instep and the upright part over the heel. These 95 two members *a* and *b* are united by means of suitable reduced terminals in the directions desired, provided with buttons and button holes or other of the numerous fastening devices adapted to fastening boots, gloves, &c. 100 Or they may have neatly attached straps, elastic or otherwise provided with such or any similar means for fastening them.

Referring to the drawings Figure 1. is an

inverted view of the device illustrating my invention. Fig. 2. is a side perspective view, in both these views the heel fastening is unbuttoned. Fig. 3. is like the first two a perspective view, but unlike them the guard is buttoned and appears in natural position much as it would appear if it were in use on a boot, the boot not being shown. Figs. 4. and 5. are perspective views of opposite sides 10 of a boot including the boot guard or protector buttoned thereon. Figs. 6. 7. 8. and 9. are similar views drawn to illustrate the many variations in artistic form, and in fastening straps or terminals, that may easily be made 15 at the suggestion of fashion or the trade.

Like letters of reference designate the same or corresponding parts in all the figures.

It will be readily inferred from the illustrations, that the whole device may be cut from 20 one piece of leather, waterproof or other fabric or material, or the device may be made up of several parts united by fanciful stitching or other means used and approved in the art for similar purposes.

25 The ladies will most appreciate this invention though it obviously applies in the case of any fine boot, and they need not be reminded of the annoyance and chagrin with which they have so often observed the ruined 30 condition of the finished surface of an elegant pair of boots, caused by the chafing, mainly of the skirts and like wearing agents. Nor will the ladies fail to appreciate at a glance the great economy as well as comfort and satisfaction 35 obviously to come from the use of so simple, complete, useful and effective a device. It is obvious that constructed as illustrated in Figs. 1 to 5 inclusive, it will ordinarily not be necessary in removing the guard to unfasten 40 ten except about the ankle, it being practicable to slip the guard from the toe of the boot when the ankle fastening is released. So in putting on it may slip on in like manner already buttoned under the foot.

45 I claim—

1. The boot and shoe protector as constructed viz: having a front or instep protecting

member tapered both upwardly and downwardly from a wider central portion to which the side and bottom connections are united, 50 and a rear protecting member also made with a taper both upwardly and downwardly from a central wider portion to which the side and bottom connections are united, together with said side and bottom connections of any suitable construction, substantially as described. 55

2. The two guards united at the sides and underneath by strap-like connections, the rear one being constructed of a form tapering both upwardly and downwardly, and the front one 60 also being constructed of a form tapering both upwardly and downwardly but having also a central narrower waist part between the bases of said front tapering parts, substantially as described.

65 3. A boot and shoe surface protector cut from a single piece of material and having two narrow surface guards to extend up and down longitudinally one over the instep part and one over the surface above the rear end 70 of the boot or shoe heel and having narrow prolongations for connections, provided with fastenings about the ankle and under the boot or shoe, substantially as and for the purpose set forth.

75 4. In a boot and shoe protector constructed for attachment over the boot as specified, the front guard having both an upwardly and downwardly projecting tongue substantially as shown and described.

80 5. In a boot and shoe protector constructed for attachment over the boot as specified, the rear guard having both an upwardly and a downwardly projecting tongue, substantially as shown and described.

85 6. In a boot and shoe protector constructed for attachment over the boot as specified, the front and rear guards both provided with the central tongue like extensions substantially as shown and described.

H. J. WESCOTT.
